UNITED STATES PATENT OFFICE.

LEE SHA KUN, OF VICTORIA, BRITISH COLUMBIA, CANADA.

CONSTRUCTION OF SEA-GRASS, CANE, AND WILLOW CHAIRS.

Application filed December 1, 1926, Serial No. 151,960, and in Canada November 26, 1925.

My invention relates to the construction of chairs in which such materials as sea-grass, cane, willow and the like are largely used, and specifically to the method of 5 structuring the legs of such chairs.

The object of the invention is to prevent the loosening of the cane or other like material at its point of termination at the foot of the chair leg, as usually obtains in this 10 class of chair when the common methods of construction are followed.

It is a well recognized fact that in almost all chairs of this class the pliable material which is used to plait, weave, or twist 15 around the leg invariably becomes detached at the foot, ultimately causing the ruin of the chair.

The seat of my invention is the elimination of this defect, which I accomplish by 20 introducing a method of locking the terminal convolutions of the weave near the foot of the chair leg.

My method is more clearly understood by 25 reference to the drawings herewith which form part of this application, in which Fig. 1 is a general view or front elevation of the lower end of the leg of a chair of the type in question, showing my improved construction.

30 Fig. 2 is a cross section of the same.

Fig. 3 is a half vertical section of Fig. 1, and

Fig. 4 is an enlarged view of the locking 35 of the weave.

The solid portion of the chair leg which may be of bamboo, cane, or other suitable wood, is indicated by (a), around which 40 convolutions of cane, twisted sea-grass, or other pliable material are wound as shown at (b). The usual method is to wind from the top and secure the lowest convolution by a pin or tack; but in my method I take one or more vertical loops (c) preferably 45 of flat pliable cane, (in the drawing five of these elongated U-shaped loops are shown,) the inner member of the loop is laid flat against the wood core (a) whilst the outer member is arranged so as to form a weave 50 with the convolutions (b), the U-shaped loop passing around the lowest convolution thence being threaded alternately over and

under every alternate one or more of the convolutions (b), and being finally secured underneath the upper convolutions of the leg winding. The terminal of the lowest 55 convolution (b) is tucked in underneath the superposed convolution and thus firmly secured by them as shown at (d). If preferred the winding of the leg may commence with the member (d) and proceed from the 60 foot upwards weaving in the loop member (c) alternately as the convolutions proceed.

The arrangement of the locking member (c) is clearly shown in Fig. 3 and Fig. 4; the full lines in Fig. 4 show the shape of the 65 member (c) before it is woven into the convolutions. Pliable cane flat and relatively thin is here shown as the most preferable form used; the dotted or broken lines (e) in Fig. 4 show the final shape of the locking member, the inner member of the loop being (f) and the outer member (g).

It will thus be seen that with my construction the loosening of the lower convolutions forming the covering of the legs of this type 75 of chair is entirely prevented, as these convolutions are positively locked and securely held in place by the weave mechanism.

What I claim as my invention and desire 80 to secure by Letters Patent, is:

1. In a chair leg of the type described, a central solid core, said core being covered externally with convolutions of pliable material, a loop of flat pliable material, said loop embracing the lowest of said convolutions and having its outer member interlaced with the said convolutions and secured 85 thereby.

2. In a chair leg of the type described, a central solid core, said core having wound 90 upon it a series of convolutions of pliable material, loops of flat pliable material of the shape of an elongated U, the said loops having their open ends uppermost, one member of each of said loops lying flat against the said core and parallel thereto, the outer member of the said loop embracing the lowest of the said convolutions and being interlaced right-angularly with the said convolutions through which it is threaded 95 in alternate order.

LEE SHA KUN.
